RAILWAY CAR FLOOR

De Witt R. Arnold, Evanston, Ill., assignor, by
mesne assignments, to Standard Railway
Equipment Manufacturing Company, a corpo-
ration of Delaware

Application June 1, 1937, Serial No. 145,886

4 Claims. (Cl. 105—422)

The invention relates to floors more particularly designed for use in railway freight cars and has for its object the obtaining of a more durable construction and one having various other advantages. To this end the invention consists in the construction as hereinafter set forth.

In the drawing:

Figure 1 is a longitudinal section through a portion of a car floor of my improved construction;

Figure 2 is an enlarged view similar to Figure 1;

Figures 3 and 4 are similar views showing modified constructions;

Figure 5 is a plan view of the construction shown in Figures 2 and 3.

Heretofore, certain railway freight car floors have been provided with a metallic covering for portions of the area thereof subjected to the greatest wear. However, inasmuch as it is necessary to provide for nailing down the blocking for holding the lading from shifting, this metal facing plate is apertured or slotted to permit the driving of nails into the wooden floor therebeneath. A serious objection to such construction is that with certain types of lading, such for instance as material held in paper or cloth sacks, the uneven surface formed by the apertures in the plate will do injury. To overcome this defect I have designed a construction which still retains the metallic facing apertured for the passage of nails, but which provides an unbroken upper surface for support of the load. This is preferably accomplished by the filling of the apertures in the metal facing plate with a plastic material having its upper surface flush with the upper surface of the impervious parts. This will still permit of driving the nails, but when these are withdrawn the plastic nature of the material will soon heal the breach.

My improved construction may be applied either to the entire car floor or only to a part thereof. Where applied to the entire floor, it is possible to construct the wooden portion of thinner material than that generally used and to still retain the same strength, by reason of the metallic reinforcement. As shown in Figure 1, A are the match wooden floor boards, and B the metal facing plates covering the same. The plates B are provided with a series of apertures C suitably spaced for convenience in the nailing of the blocking. These apertures C are all filled with a mastic or other plastic compound D of such a nature and of such viscosity that while it will adequately support the load placed thereon, it

will permit of driving a nail therethrough. Also, when the nail is withdrawn the displaced material will flow back to close the opening. Various plastics may be used for this purpose, but I have found a suitable material to be that commercially known as "#5 red caulking cement" put out by the Continental Works Company of Chicago, Illinois.

As shown in Figure 2, the metallic facing B is laid directly in contact with the floor boards A and the plastic material D is used only to fill the apertures C. In Figure 3, the plastic material extends over the whole surface of the wooden floor, as indicated at E, the facing plate A being laid thereon and with plastic material D filling the apertures. In Figure 4, the plastic material not only extends under the facing plate as at E, but also over the same as at F, as well as filling the apertures C. In each of these constructions the top surface is level and forms a support for the load, and also in each, nailing of the blocking is permitted, while the openings formed when the nails are withdrawn are healed by the plastic material.

What I claim as my invention is:

1. A car flooring comprising a wooden underfloor, a metallic sheathing covering the upper face of said wooden floor provided with a plurality of apertures of sufficient size for convenient insertion of laden securing means, thereby leaving open areas into which certain types of laden may enter to the injury thereof when dragged over the floor, and a penetrable plastic material filling the apertures in said sheathing.

2. A car flooring comprising a wooden underfloor, a metallic sheathing covering the upper face of said wooden floor provided with a plurality of apertures of sufficient size for convenient insertion of laden securing means, thereby leaving open areas into which certain types of laden may enter to the injury thereof when dragged over the floor, and a penetrable self-healing plastic material filling the apertures in said sheathing.

3. A car flooring comprising a wooden underfloor, a metallic sheathing covering the upper face of said wooden floor provided with a plurality of apertures of sufficient size for convenient insertion of laden securing means, thereby leaving open areas into which certain types of laden may enter to the injury thereof when dragged over the floor, and a penetrable self-healing plastic material filling the apertures in said sheathing and presenting an unbroken top surface for supporting the lading.

4. A car flooring comprising a wooden underfloor, a metallic sheathing covering the upper face of said wooden floor and provided with a plurality of apertures of sufficient size for convenient insertion of laden securing means thereby leaving open areas into which certain types of

laden may enter to the injury thereof when dragged over the floor, and a penetrable plastic material covering the surface of said underfloor and extending upward into the apertures in said sheathing.

DE WITT R. ARNOLD.
